Attorney

UNITED STATES PATENT OFFICE.

THOMAS COOK, OF STALYBRIDGE, ENGLAND.

BALING PRESS.

Application filed July 15, 1920. Serial No. 396,534.

To all whom it may concern:

Be it known that I, THOMAS COOK, subject of the King of Great Britain and Ireland, and resident of Stalybridge, in the county of Chester, England, have invented certain Improvements in Baling Presses, of which the following is a specification.

This invention relates to improvements in baling presses for use in the baling of all kinds of materials which require to be compressed into small compass, and particularly refers to presses of the vertical type; the object being to provide a novel general arrangement of the press; means for controlling the downward movement of the platen; and means for controlling the movement of the strap fork rod, so that the machine cannot be started into action without the full cognizance of the operator.

My invention will be fully described with reference to the accompanying drawing in which:

Fig. 1, is a front elevation of a baling press constructed in accordance with my invention,

Fig. 2, elevation from the left hand end,

Fig. 3, elevation from the right hand end, and

Fig. 4, plan.

Fig. 5 is a detail view of the catch mechanism showing the parts 12, 13 and 21.

With the aforesaid objects in view the main body of the press is built up from steel or like bars *a*, beams *b* and stanchions secured together in any suitable form. Where a closed press is required, the framework is covered in with metal or wood sheets *c*, leaving, however, openings at the front and back through which the material is fed to or taken out of the machine. When a sufficient amount of material has been placed in the machine it is pressed into small compass by a movable platen *d*, the openings referred to being closed during pressing by doors *e* mounted on hinge pins *f*, the doors being suitably held in closed position.

An important feature of my invention relates to means for driving the vertically movable platen *d*. For this purpose the latter has an arm or stud *g* at each end passing through a slot *h* in the side of the press frame. To each of these arms is adjustably connected the end of a wire cable *i* or its equivalent which passes round guide pulleys *j* and *k*, mounted on studs *m* and is then anchored to the outermost point of a drum

preferably a scroll or fusee drum *n*. Two of these drums *n* are fixed on the ends of a shaft *o* located, along with the gear for driving them at the base of the press, so that as the drums or scrolls *n* are rotated an increasing pressure is gradually brought to bear on the material being compressed between the movable platen *d* and the fixed head *p* of the press, the greatest pressure occurring in the case of scrolls when the cables reach the smallest diameters of the latter. The end of each cable is fastened to the fusee at its largest diameter, so that the cable gradually winds from the larger end to the smaller end, increasing the power and decreasing the speed.

The scroll or other drums *n* are driven by spur pinions *q* and wheels *r* giving suitable reductions from the driving shaft *s*. The latter is provided with fast and loose pulleys *t* and *u* at one end and a brake drum *v* at the other. It also carries pinions *w* gearing into wheels *x* on the second motion shaft *y*, this latter carrying the pinions *q* previously mentioned as part of the reduction gear. The brake drum *v* co-acts with a pivoted brake shoe *z* which is brought against the brake drum to stop the rotation of the driving gear when the driving belt is on the loose pulley *u* and as the platen *d* descends to its lower position. The platen *d* puts the shoe in action by means of a rod *3*, having a bent end *4*, and link connections with the shoe. The platen engages the end *4* as it descends and moves the lever or arm *5* about its pivot pin *6*.

The driving strap is automatically shifted from the fast *t* to the loose pulley *u*, also by the action of the platen, to stop the press when the desired density of compression has been reached. This is carried out by means of a rod *7* and a link or lever connection having a bent end *8* to engage the platen in its upward stroke operating in conjunction with a sliding strap fork rod *9*. The rod *7* is connected to a short shaft *10* by arm *11*, such shaft having fixed on it another arm or catch *12* the free end of which engages with a recess *13* in the strap fork rod *9* to hold the latter in position during the pressing operation and keep the strap fork *14* opposite the fast pulley *t*. In this position a spring *15*, having one end secured to the rod *9* at *16* and the other coupled to a fixed stud *17*, is stretched ready for retraction when the required pressure between the

platens has been reached. The spring is put in the charged position by sliding the strap fork rod 9 in its brackets 18 by the agency of handle 20. At the required point of compression the platen α lifts the rod 7 referred to, disengages the catch 12 and allows the spring 15 to slide the strap fork rod and ship over the belt to the loose pulley u. When the belt is on the loose pulley, 10 the catch 12 is in engagement with a notch in the top of a boss 21 on the rod 9 and the latter can only be set in position for starting the press by first lifting the pivoted catch by means of handle 22 so that the 15 operator is always fully conscious that he is starting the press into motion.

What I claim as my invention and desire to secure by Letters Patent is:—

1. In a press, a vertical press chamber 20 having vertical slots in its sides, a press platen provided with arms which project laterally through the said slots, lower guide sheaves carried by the said arms, upper guide sheaves carried by the press chamber, 25 flexible connections secured at one end and passing over the said sheaves, fusee drums having the free ends of the flexible connections secured to their larger end portions, and means for revolving the fusee drums simultaneously, and thereby raising the 30 platen with a constantly increasing pressure.

2. In a press, a vertical press chamber having a vertical slot in one side, a press 35 platen, means for raising the press platen provided with a revoluble brake drum, a

pivoted brake shoe for bearing on the brake drum, and a tappet rod having an end portion which projects through the said slot below the platen, said rod being operatively 40 connected with the pivoted brake shoe so that the brake is applied by the platen before the platen completes its down-stroke.

3. In a press, a vertical press chamber having a vertical slot in one side, a press 45 platen, means for raising the platen provided with fast and loose belt pulleys, a belt-shifting rod, a spring for sliding the said rod to move the belt from the fast pulley to the loose pulley, a pivoted catch 50 which normally engages with the said rod, and a tappet rod having an end portion which projects through the said slot above the platen, said tappet rod being operatively connected with the said catch so that 55 the belt is shifted onto the loose pulley by the spring before the platen completes its upstroke.

4. In combination with a press as set forth in claim 3, a notched boss on the said 60 belt-shifting rod which engages with the said pivoted catch when the belt is on the loose pulley and thereby prevents the belt-shifting rod from being operated until the pivoted catch is disengaged by hand. 65

In testimony whereof I have hereunto set my hand in the presence of two witnesses.

THOMAS COOK.
